UNITED STATES PATENT OFFICE.

WILLIAM G. TAYLOR, OF SCHENECTADY, NEW YORK, ASSIGNOR TO GENERAL ELECTRIC COMPANY, A CORPORATION OF NEW YORK.

MOTOR CONTROL.

1,347,305.

Specification of Letters Patent. Patented July 20, 1920.

Application filed May 29, 1917. Serial No. 171,774.

To all whom it may concern:

Be it known that I, WILLIAM G. TAYLOR, a citizen of the United States, residing at Schenectady, in the county of Schenectady, 5 State of New York, have invented certain new and useful Improvements in Motor Control, of which the following is a specification.

My invention relates to the drive of embossing machines and the like and it provides improved means whereby the drive may be effected in an improved manner.

More specifically my invention relates to the control of electric motors and it provides improved means whereby the motors may be started and stopped and generally controlled in a safe, reliable and efficient manner.

My invention has a particular utility in drives for leather embossing machines and the like. Heretofore, in such machines, mechanism has been provided whereby a portion of the hide is embossed, after which the hide must be manually shifted to another position so as to emboss another portion. The drive for such machines has heretofore been such that the output of the machine has been very limited because the operator has had so many things to look after 25 and to operate manually. One of the objects of my invention is the provision of an arrangement whereby after the hide is once placed in position to be operated upon by the embossing apparatus, the successive operations of embossing, shifting the hide, etc., are all automatically performed without the necessity of any attention to the machinery itself from the operator, the arrangement, however, being such that the operator has 30 at all times complete manual control of the operation of the machine at starting or in case for any reason it should become necessary to assume manual control during the automatic operation.

It is necessary that the hide be shifted an exact distance after each embossing operation in order that there shall be neither blank nor overlapped spaces between the successive embossed sections and my invention has for one of its objects the provision of an arrangement whereby this exact cooperation between the embossing mechanism and the means for shifting the hide is obtained.

In carrying my invention into effect I

preferably provide an electric motor to operate the embossing mechanism, which is ordinarily a roller adapted to reciprocate back and forth across an embossing plate or bed, and another electric motor to operate 60 the mechanism for shifting the hides, usually an endless carrier on which the hides are placed. I provide an improved control arrangement for these motors, each driving a separate load and performing a separate 65 function, so that the operations of the motors are coördinated and each will perform its required function in the proper sequence for the proper operation of the machine. The functions of these motors are coördinated so 70 that, after the embossing roller has completed its movement in one direction, it is stopped and the motor driving the endless belt carrier on which the hide is placed, is energized, so as to shift the hide the exact dis- 75 tance corresponding to the width of the embossing plate, after which, the motor driving the embossing roller is energized to reverse its direction of operation and move the roller back across the hide, this sequence 80 of operations continuing until the source of supply to the motors is cut off or the operator assumes manual control of the machine.

After the machine is properly started the attention of the operator is ordinarily not 85 required other than to put new hides on the endless carrier and observe the operation on the hides. My invention further provides an arrangement whereby the operation of the driving motors may be arrested at any 90 point or the machine be started, stopped or reversed at the will of the operator without destroying this coöperative relation of the motors, by means of push buttons or the like conveniently located at the operator's position by the machine.

By means of my invention, the output of the machine is greatly increased because the interval between the successive operations is reduced to the practical minimum and 100 because of the fact that the time of the operator is practically entirely devoted to placing new hides on the carrier and observing the embossing operation without the necessity, ordinarily, of any of his time 105 being taken to control the operation of the machine, since after the machine is started properly all the various functions are automatically controlled.

For a better understanding of my inven- 110

tion reference is had to the following description taken in connection with the accompanying drawing wherein I have disclosed one embodiment of my invention.

5 Referring to the drawings, Figure 1 shows in simplified diagram, my improved control system in which the operations of a plurality of driving motors are automatically coördinated or manually controlled at the 10 will of the operator. Fig. 2 is a simplified diagram of an embossing machine showing electric driving motors for operating the embossing roller and for shifting the endless carrier on which the hides to be embossed are placed.

15 Referring first to Fig. 2, the endless carrier 1 on which the hides are placed by the operator is adapted to be shifted by means of the electric motor B which drives the 20 drum 2. A friction clutch arrangement is provided between the drum 2 and the worm and gear driven by the motor B. A limit switch L for controlling the operation of the motor A which drives the embossing roller 25 is directly connected to and operated synchronously with the drum 2 driven by the motor B. The embossing roller 3 is adapted to be reciprocated back and forth across the embossing bed or plate 4 in a plane at right 30 angles to the plane of the drawing by means of the motor A through any suitable mechanism such as a worm drive (not shown). The embossing roller 3 is yieldingly supported by means of the springs 5. The 35 limit switch P which controls the operation of the shifting motor B is shown as being geared to the motor A, although it will be readily understood that it can also be operated in any well known manner, such as 40 by the roll itself at each end of travel.

45 The operations of the motors A and B are coördinated by means of my control arrangement shown diagrammatically in Fig. 1 so that when the embossing roller 3 has proceeded across the embossing plate 4 to a 50 limit of travel where the roller is free from the hide, the motor A is deenergized and brought to rest by means of a dynamic braking action whereupon the motor B is energized to shift the hide forward a distance corresponding exactly to the width of the embossing roller. After the hide has been 55 thus shifted, the motor A is energized to operate in the reverse direction and return the embossing roller back over the embossing plate, thus embossing another section of the hide, this automatic operation continuing until the operator assumes manual control of the machine or until the source of 60 supply to the motors is cut off. In order that the hide shall be shifted an exact distance corresponding to the width of the embossing roller I have provided an electro-magnetically actuated dog 6 which is 65 adapted to engage projections 7 on the drum

2, the arrangement being such that the electromagnet 8, adapted to move the dog 6 against its bias into engagement with one of the projections 7 on the drum 2, is not energized until a certain interval after the 70 shifting motor B is energized. The dog is thus permitted to escape the first projection but nevertheless engage the next succeeding and thus arrest the carrier 1 exactly at the new position. Since the projections 7 are 75 spaced apart a distance equal to the width of the embossing roller, gaps and overlapped portions in the embossing of the hide are thereby avoided. The coil 8 is energized responsively to the energization of the 80 motor B and is deenergized simultaneously with the motor B so that the dog 6 can move out of engagement with the projections 7 and thereby permit the motor B to again move the hide when the embossing 85 roller has completed its next movement across the embossing plate and become free from engagement with the hide 9.

90 Referring to Fig. 1 the motor A which drives the embossing roller 3 back and forth across the embossing plate is shown as having an armature 10, shunt field 11, and a commutating field 12. This motor is energized to operate in the forward direction by means of the electro-magnetically actuated switch or contactor F, and in the reverse direction by means of the electro-magnetically actuated switch or contactor R. The normally closed contactor D is adapted to be closed in accordance with the bias of the 95 spring d when the contactors F and R are open and include the motor armature and commutating field in a dynamic braking circuit including the resistance 13, this circuit being maintained closed until the motor has 100 been brought substantially to rest by means of the spring d and the coil of the contactor D energized responsively to the armature voltage of motor A. A system of pivoted 105 mechanical interlocks 14 and 15 is provided for opening the dynamic braking contactor D against its bias when either one of the contactors R or F is closed, the interlocks likewise preventing the simultaneous operation of both the contactors R and F, in a 110 well known manner. Included in the armature circuit of the motor A is an accelerating contactor 16 of the well known series type, adapted to be maintained opened as long as the armature current at starting is 115 above a predetermined value, and to close, short circuiting the starting resistance 17, when the current has dropped below this predetermined value. The rheostat 18 in the motor armature circuit and the rheostat 120 19 in the motor shunt field circuit are provided for varying the speed of the motor in a well known manner.

125 The motor B which drives endless carrier 1 is adapted to be energized from the source 130

of supply 20, 21, by the closing of the electromagnetically actuated switch or contactor 22. Auxiliary switches 23 and 24 operated by the contactors R and F are included 5 in the coil circuit of the electromagnetic line switch 22, and the arrangement is such that both of the contactors R and F must be open and the motor A disconnected from the source of supply before the contactor 22 can 10 be energized to close the armature circuit of the motor B. The contactor 22 likewise controls the energization of the time limit relay 25 which controls the energization of the coil 8 provided for operating the dog 6, the 15 arrangement being such that after the contactor 22 is closed the movement of the plunger of the time limit relay is retarded by means of the dash pot 26 so that the coil 8 will not be energized until a predetermined 20 interval after the closing of the contactor 22.

The limit switch L, directly connected to and operated synchronously with the drum 2 has a plurality of contact segments which engage stationary contacts for controlling 25 the energization of the contactors R and F. This limit switch L is moved to the next operative position each time the motor B completes its movement of shifting the hide, (the number of operative positions depending on 30 the number of projections 7 on the drum 2) and the coil of either one of the contactors R or F is thereupon energized to close its switch contacts and energize the motor to operate in a reverse direction from that previously operated. The limit switch P, 35 shown as being geared to the motor A is moved to a new operative position when the embossing roll has reached an end of travel. When the limit switch P is thus moved, the 40 motor A is deenergized, and connections are made whereby the next operation of the limit switch L will reverse the motor A, and the motor B is energized so that the hide may be shifted. The manually operated 45 switch 27, which will ordinarily be a snap switch, although not so shown in the drawing, is provided for quickly deenergizing the motors and stopping the machine at the will of the operator. The manually operated 50 push buttons 28 and 29 are provided for controlling the energization of the coils of contactors R and F so that the motor A may be energized for operation in one direction, stopped or reversed at the will of the operator. By means of the switch 27 and the 55 push buttons 28 and 29 the operator is able to move the embossing roller back and forth across the embossing plate, independently of the positions of the limit switches L and P. 60 As thus constructed and arranged the operation of my invention is as follows:

It will be assumed that the embossing roll 3 is at a limit of travel and that the hide 9 has been placed on the endless carrier 1 65 in a position so that the next operation of

shifting the hide will bring it into proper position between the embossing roll and the embossing plate. The manually operated switch 27 will first be moved to the right at the position where the left hand blade 70 of the switch makes engagement with the middle contact. This is to insure that the machine will not start operating until the operator desires after he has closed the line switch 30. After the line switch 30 75 has been closed the switch 27 can be moved to the left to the position shown in the drawing, whereupon the coil of the line contactor 22 will be energized through a circuit from the supply conductor 20, the 80 left hand blade of switch 27, contacts of limit switch P right hand blade of switch 27, auxiliary switches 23 and 24 to the other supply conductor 21. The contactor 22 will close, energizing the motor B from the 85 source of supply and causing the endless carrier 1 to be shifted so as to move the hide into proper position between the embossing plate and the embossing roller. The closing of the contactor 22 also energizes the 90 coil 25 of the time limit relay and the plunger of this relay will be moved upward against the retarding influence of the dash pot 26. After an interval determined by the setting of the dash pot 26, the relay will 95 close its contacts and energize the coil 8 of the restraining device, but this coil will not be energized until after the first projection 7 on the drum 2 has been cleared. When the motor B has shifted the hide the exact 100 distance corresponding to the width of the embossing roller, the dog 6 will engage the next projection 7 and thus arrest any further movement of the hide, the friction clutch drive between the motor and the drum 105 2 permitting a slippage between the drum and the drive connection. It is intended that the motor B shall be deenergized a short interval after the hide has been shifted to the new position, and this is brought 110 about by means of the limit switch L which is driven from the motor B. After the motor B has shifted the hide a predetermined distance the limit switch L will have been moved so as to make engagement with the contacts 32, 33 and break the engagement with the contacts 34, 35. This will cause the coil of reversing contactor R to be energized through a circuit from the supply conductor 20, left hand blade of 115 switch 27, limit switch P, contact 32, limit switch L, contact 33, to the other supply conductor 21. The contactor R is thereby closed energizing the motor A from the source of supply. The closing of contactor 120 R will open the dynamic braking contactor D by means of the interlock 14, and the auxiliary switch 23 will be opened thus opening the coil circuit of contactor 22, causing this contactor to open and discon- 125 130

nect the motor B from the source of supply. The motor A will therefore start and when the current in its armature circuit has dropped to a predetermined value the series 5 contactor 16 will close, short circuiting the starting resistance 17 and accelerating the motor to the full speed as determined by the setting of the rheostat 18 in the motor armature circuit and the rheostat 19 in the motor 10 field circuit. The embossing roll will be moved back over the embossing plate and thus emboss a section of the hide. When the roll has completed its operation in this direction and is free from the hide, at a predetermined 15 limit the movement of the limit switch P to the next operative position is completed, thereby deenergizing the coil of the contactor R and permitting this contactor to open at the same time closing the auxiliary switch 23. Likewise, connections 20 are made through the limit switch P so that when the limit switch L is next operated the motor A is reversed. As soon as the contactor R opens, the dynamic braking contactor D will be closed in accordance with its bias and connect the armature of motor A in a dynamic braking circuit including the resistance 13, thus bringing the motor A and the embossing roll to rest quickly. 25 The closing of the auxiliary switch 23 will complete the circuit to the coil of contactor 22 and this contactor will be energized to close, connecting the motor B to the source of supply so as to again shift the hide in the same manner as that previously explained. After the hide has been shifted 30 the limit switch L will have been moved so as to energize the contactor F and thus reverse the motor A and cause the embossing roll to be returned across the embossing plate and emboss another section of the hide. This automatic operation of the various parts of the machine and the control equipment will proceed without any attention from the operator and his attention 35 can be directed entirely to an observation of the embossing operation and to placing new hides on the endless carrier.

In case the operator should desire at any time to arrest the operation of the machine, 40 he can do so by simply moving the switch 27 to the right, thereby deenergizing both motors. After he has done this he can control the operation of the machine at will by means of the push buttons 28 and 29; thus, by pressing the push button 29 the coil of the contactor R can be energized 45 and the motor A operated to cause the embossing roll to proceed across the embossing plate in the direction determined by the closing of this contactor. Likewise, with the push button 29 in the position shown in the drawing, by depressing the push button 28 the coil of contactor F can be energized 50 to cause the motor A to operate in the other

direction. Pressing both push buttons simply opens the circuits to both contactors. By means of these push buttons and the switch 27 the operation of the machine can be controlled at the will of the operator independently of the limit switches L and P. When the operator desires that the automatic operation of the machine shall proceed all that he need do is to release the push buttons 28 and 29 and move the switch 55 27 to the left, the position shown in the drawing. The circuits made by the operation of the push buttons 28 and 29 are easily traced and it is thought that they will be readily perceived by an inspection 60 of the drawing.

While I have described my invention as embodied in concrete form and as operating in a specific manner in accordance with the provisions of the patent statutes, it 65 should be understood that I do not limit my invention thereto since various modifications thereof will suggest themselves to those skilled in the art without departing from the spirit of my invention, the scope 70 of which is set forth in the annexed claims.

What I claim as new and desire to secure by Letters Patent of the United States is:—

1. The combination with a machine having an intermittently operated mechanism, of an electric motor for operating the same, a second intermittently operated mechanism coöperating with the first mechanism, an electric motor for driving the same, a 95 mechanical stop for accurately stopping the second mechanism after a predetermined travel, a switch operated by each motor for controlling the other motor, and connections whereby the motors are operated in 100 succession.

2. The combination with a machine having a reciprocating mechanism, of an electric motor for reciprocating the said mechanism, a second mechanism coöperating with the first mechanism and an electric motor for operating the same, a limit switch for each of said motors operated by the other motor, electromagnetic switches and connections controlled by the said limit 115 switches for automatically stopping and reversing the first motor when the first mechanism reaches an end of travel and energizing the second motor to shift the second mechanism before the first motor is reversed after it is stopped, means energized 120 responsively to the energization of the second motor to arrest the movement of the second mechanism after it has been shifted a predetermined distance, and manual control means including a plurality of push buttons for controlling the energization of the first motor and the movement of the first mechanism independently of the said limit switches.

3. The combination with two electric motors, of controlling means for the same comprising limit switches, each limit switch operated by one of the motors to control the 5 operation of the other motor, switch mechanism controlled by the limit switches, and connections whereby the one motor is automatically periodically reversed at predetermined limits of travel and the other 10 motor is automatically energized to operate during a predetermined interval before the one motor is reversed after this one motor has reached a predetermined limit of travel.
4. The combination with two electric 15 motors, of controlling means for the same comprising limit switches each limit switch operated by one of the motors to control the operation of the other motor, switch mecha-

nism controlled by the limit switches, connections whereby the one motor is periodically reversed at predetermined limits of travel and the other motor is automatically energized to operate during a predetermined interval before the one motor is reversed after this one motor has reached a predetermined limit of travel, and manually operated control means including a plurality of push buttons for controlling the said switch mechanism independently of the said limit switches whereby the one 25 motor is started, stopped or reversed with its relation to the other motor preserved.

In witness whereof I have hereunto set my hand this 28th day of May, 1917.

WILLIAM G. TAYLOR.
